UNITED STATES PATENT OFFICE.

ARVID JOHNSON, OF DULUTH, MINNESOTA.

SAW-SET.

No. 883,806.

Specification of Letters Patent.

Patented April 7, 1908.

Application filed November 4, 1907. Serial No. 400,442.

To all whom it may concern:

Be it known that I, ARVID JOHNSON, a subject of the Emperor of Russia, residing at Duluth, in the county of St. Louis and State 5 of Minnesota, have invented a new and useful Saw-Set, of which the following is a specification.

My invention relates to improvements in saw-sets; and the object is to provide a saw-set that will be efficient and also convenient for use in lumber camps and like places, for setting the teeth of saws used in felling trees.

In the accompanying drawing, Figure 1 is a side elevation of my improved saw-set 15 mounted upon a piece of lumber serving to support it when in use, and a portion of a saw blade in position to be set by the device. Fig. 2 is a top view of Fig. 1 with the wooden supporting block omitted. Fig. 3 is a trans- 20 verse section on the line *a—a* in Fig. 1 with the wooden block omitted.

Referring to the drawing by reference numerals; 4 designates the steel block serving as the anvil in the device. It is securable to 25 mostly any kind of wooden support 5 by having in a notch 6 in one end of it pivoted at 7 an angularly bent prong or hook 8 adapted to be driven horizontally into the wood, and near the other end of it a bottom prong 9 30 adapted to be driven downward into the wooden block, plank or log 5. On the pivot 7 is also attached a hand lever 10, which bears at 11 upon the free end of another lever 12, which is pivoted at 13 in a notch in 35 the front end of the anvil 4. Through apertures 27 in both of said levers is guided to slide vertically the punch 14 by which the saw teeth are set when the punch receives a blow on its upper end. The lower end of the 40 punch and the part of the face of the anvil operated upon are therefore beveled to the extent it is desired to have the saw teeth set, as can be seen in Fig. 1, where 15 is the saw and 16 a tooth operated on after it has been 45 placed against a gage 17. Said gage is guided by having fingers 18 (see Fig. 3) movably guided in grooves 19, which in both 50 sides of the anvil extend parallel to the beveled face 20 thereof. The plate is held in any forward or rearward position by having an 55 arm 21 with a slot 22 in it for a thumb-screw 23 which is threaded in the side of the anvil and thus able to hold the arm clamped thereto in any adjusted position according to the length of the saw tooth or part of it that is to be set. The saw, while operated on, is

held firmly down on the anvil by a spring arm 24 secured at 25 to the anvil and having its front end curved upward so as to receive pressure from the lower lever 12 of the compound levers 10—12; the operator bearing down on the lever 10 with one hand while striking on the punch with a hammer held in the other hand; and when he raises the lever 10 the spring 24 raises from the saw-blade 65 and by the lever 12 and a pin 26 in the side of the punch also lifts the punch, so that the saw blade is free to be moved with the next tooth into position for operation, which is thus repeated until all the teeth are set. 70 The apertures 27 are elongated in longitudinal direction of the levers and upon each lever is held by a thumb-screw 28 a plate 29 having a slotted hole for said thumb-screw and a guiding hole for the punch 14 so that 75 by adjusting the plates by said thumb-screws the punch is adjusted so as to cover more or less of the beveled face of the anvil. From this it will be understood that the guide 17 and punch 14 may be moved rearwardly on the anvil until even the shortest saw teeth may be set by the device. 80

Having thus described my invention, what I claim is:—

1. The combination with an elongated 85 steel anvil having near one end of its upper side a beveled or inclined face on which to set the saw teeth, a setting punch arranged to slide vertically above said face, a spring arm fixed near the other end of the anvil and 90 extending toward the end having the beveled face, said arm having its body offset from the anvil to permit the saw blade to pass below it, and its free end curved upward higher than the body, a lever pivoted at one 95 end of the anvil and adapted to press upon the end of the spring arm and thus hold the saw firmly upon the anvil, a saw-setting punch slidingly inserted vertically in an aperture in the lever and having its lower end 100 beveled parallel to the beveled face of the anvil, and means whereby the lever will engage the punch and elevate it.

2. The combination with an elongated 105 steel anvil having near one end of its upper side a beveled or inclined face on which to set the saw teeth, a setting punch arranged to slide vertically above said face, a spring arm fixed near the other end of the anvil and 110 extending toward the end having the beveled face, said arm having its body offset from the anvil to permit the saw blade to

pass below it, and its free end curved upward higher than the body, a lever pivoted at one end of the anvil and adapted to press upon the end of the spring arm and thus hold the saw firmly upon the anvil, a saw - setting punch slidingly inserted vertically in an aperture in the lever and having its lower end beveled parallel to the beveled face of the anvil, and means whereby the lever will engage the punch and elevate it; a second lever pivoted to the other end of the anvil and adapted to press upon the first mentioned lever, said second lever also having an aperture for guiding the setting punch.

3. The combination with an elongated steel anvil having near one end of its upper side a beveled or inclined face on which to set the saw teeth, a setting punch arranged to slide vertically above said face, a spring arm fixed near the other end of the anvil and extending toward the end having the beveled face, said arm having its body offset from the anvil to permit the saw blade to pass below it, and its free end curved upward

higher than the body, a lever pivoted at one end of the anvil and adapted to press upon the end of the spring arm and thus hold the saw firmly upon the anvil, a saw - setting punch slidingly inserted vertically in an aperture in the lever and having its lower end beveled parallel to the beveled face of the anvil, and means whereby the lever will engage the punch and elevate it; a second lever pivoted to the other end of the anvil and adapted to press upon the first mentioned lever, said second lever also having an aperture for guiding the setting punch, the apertures in said levers being elongated in longitudinal direction of the levers, a guiding plate adjustably secured on each lever and 40 guidingly engaging the punch, for the purpose set forth.

In testimony whereof I affix my signature, in presence of two witnesses.

ARVID JOHNSON.
